UNITED STATES PATENT OFFICE

EDWIN HERBERT LEWIS, OF OAK PARK, ILLINOIS

ASH TRAY

Application filed November 12, 1930. Serial No. 495,156.

This invention relates to an improved method and apparatus for quenching cigarettes and the like.

The main objects of my invention are to provide apparatus which will separate the burning portion of a cigarette from the unburned portion; to provide an ash receiver having cutting edges above the ash holder; to provide means for pulling the fire from a burning cigarette; to provide a receiver for the burning portion and a separate compartment for the unburned portion; to provide in a single-piece construction a compartment for the burned portion, a compartment for the stub and a saw-tooth construction above said compartment for the burned portion.

An illustrative embodiment of my invention is shown in the accompanying drawings, in which:—

20 Figure 1 is a top plan of an ash tray embodying my invention.

Fig. 2 is a side view of the same.

Fig. 3 is a section on the line 3—3 of Figure 1.

25 In the form shown, the ash receiver 1 is made in one piece of fireproof material and comprises a heavy base 2 with a flange edge 3. Seated on the base 2 is a right cylinder 4 having substantially the same diameter as the base and forming a receptacle 5 with a depth of about two-thirds of its diameter. Concentrally mounted on the same base 2 is a second right cylinder 6 having a diameter equal to one-half the diameter of the base and 30 forming a receptacle 7 having a depth equal to the diameter of the base.

The outside cylinder 4 has a turned upper edge 8 and the inside cylinder 6 has an outwardly curled top 9 with dependent saw-tooth cutting edges 10. The saw-teeth are spaced away from the cylinder 6 a distance substantially equal to the distance that the fire extends into a cigarette.

In operation, the apparatus here disclosed 45 works opposite to the common practice of quenching a cigarette by pressure, or that of pushing or stamping the burning portion into such close relation as to shut off the oxygen supply.

50 In my improved apparatus, the burning

portion is cut away or pulled away from the unburned portion by insertion of the burning end between the sharp teeth which serve as a V-shaped cutter. An upward pull effectually cuts loose or tears loose the burning portion which drops into the outer receptacle provided for the reception of the ashes.

Owing to the loose texture of cigarettes, and the like, and the fact that the receiver is comparatively heavy, the pull required to remove the fire will not tilt or move the receiver. The central receptacle forms a convenient receiver for the reception of the stub or unburned portion of the cigarette.

Although but one specific embodiment of this invention is herein shown and described, details thereof may be modified without departing from the claims.

I claim:

1. An ash receiver comprising an ash compartment for the burned portion of the cigarette, a stub compartment for the unburned portion, and means mounted above the ash compartment and having saw-teeth for separating the burned portion from the unburned portion.

2. An ash receiver, concentric cylinders mounted on a common base and forming separate concentric compartments, means on one of said cylinders and overhanging one of said compartments for removing the burning portion of a cigarette, said means comprising converging cutting edges.

Signed at Palo Alto, California, this 8th day of November, 1930.

EDWIN HERBERT LEWIS.
